RADIANT GAS BURNER

Charles W. Morek, Jr., Philadelphia, Pa., assignor
to Selas Corporation of America, Philadelphia,
Pa., a corporation of Pennsylvania

Application June 3, 1950, Serial No. 165,954

8 Claims. (Cl. 158—99)

1

The present invention relates to burners, and more particularly to a high capacity distributor or tip to be used with radiant cup type ceramic burners.

Radiant burners of the type with which this application is concerned are disclosed and claimed in Hess Patent 2,215,079, granted September 17, 1940. Burners of this type are formed of a block of refractory material that has a cup-shaped depression in one face thereof. A combustible mixture of fuel and air is discharged into the base of the cup by a distributor member in a plurality of substantially radially directed jets. The jets are ignited as they enter the cup and are completely burned therein. The surface of the cup is heated to incandescence to project radiant heat into the space to be heated, and heat is also supplied by the products of combustion that are discharged into the space from the cup.

Fuel is supplied to burners of the type under consideration as a complete mixture by either a mixing machine or by an inspirator. In either case the mixture is supplied to the cup in a series of jets by a distributor, as noted above. The distributor comprises a ceramic piece which is formed with a plurality of passages terminating in substantially radially directed ports. The capacity of the burner is limited by the size or area of these ports and consequently the volume of fuel that can be delivered to the cup. When the ports are increased beyond a certain optimum size the burner is liable to backfire. In any event the larger the ports the smaller the turndown that can safely be obtained.

Another factor that enters into burner capacity is the pressure of the fuel supply. For a given total port area a given pressure is required to force a given amount of mixture through the distributor into the cup. When using inspirators, in particular, it is difficult to attain mixture pressures sufficient to supply the mixture in large volumes, or to have a large capacity, for a given size burner.

It is an object of the invention to provide a radiant type burner in which the port area for the mixture is appreciably increased without increasing the size of the individual passages in the distributor or tip. It is a further object of the invention to provide a distributor or tip of a given size that has a larger number of ports and total port area than it has previously been possible to obtain.

An additional object of the invention is to provide a burner having a larger capacity, or one in which a larger volume of fuel can be burned at a given pressure, than has previously been obtainable.

The burner of the present invention uses a ceramic block with the cup therein of conventional form. The distributor through which the fuel passes to the cup, however, is of a novel

2

design in the manner in which the fuel ports and passages are formed. The distributor is made of several ceramic parts so assembled that a plurality of axially displaced rows of ports are obtained. Each of these ports can be made small enough so that the danger of backfiring is eliminated over a large turn-down range. The overall area of the ports is such that for a given diameter distributor the capacity of the burner is materially increased within any pressure range.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described a preferred embodiment of the invention.

In the drawings:

Figure 1 is a sectional view of the burner;

Figure 2 is an enlarged sectional view of the distributor;

Figure 3 is a view on line 3—3 of Figure 2;

Figure 4 is a view on line 4—4 of Figure 2;

Figure 5 is a sectional view of a modified form of distributor; and

Figure 6 is a sectional view of a modified form of burner in which the fuel is supplied by an inspirator.

Burners of the present type can be used in many different kinds of furnaces, and are used in the walls, floor or roof. Wherever used the burner block itself is built into and forms an integral part of the furnace. For purposes of the present description it will be assumed that the burner is built into the wall of a furnace.

The burner is mounted in and forms a part of the furnace side wall 11. As shown most clearly in Figure 1, each burner comprises a molded block 21 of ceramic material which is secured in position in one of the side walls 11 by a suitable high temperature fire-brick cement 22. The block 21 may have different portions thereof formed of refractory materials possessing different heat resisting and thermal conducting properties, so that each portion will possess the most desirable heat resisting and thermal properties for its particular position in the block. The different portions of each block are compacted into a single unitary structure by a suitable molding operation to provide a block 21 which is rectangular in cross-section.

Block 21 is formed with a central passage 23 which extends therethrough and terminates at cup-shaped space 24 formed at the inner face of the side wall 11. Within the passage 23 is disposed a burner tube or sleeve 25 having the inner end thereof terminating at a region closely adjacent to the inner end of the passage 23. The

outer portion of tube 25 is formed with an outwardly extending shoulder 26 which fits snugly against a collar 27. The collar 27 may be a pre-formed and pre-fired body of porcelain which is thereafter united to the block 21 at the same time that the different portions of a block are united together by a firing operation. In order to position the tube 25 accurately in the passage 23, the surface of the collar 27 engaged by the shoulder 26 may be ground after the block 21 is formed. The shoulder 26 of tube 25 is positioned in an enlarged opening or well 28 extending from the outer end of passage 23 to the outer face of the side wall 11. Within the outer end of burner tube 25 is secured the inner end of a metal tube 29, as by cement, for example.

The outer end of the metal tube 29 is secured to the inner end of a short length of flexible tubing 30 which is fastened at its opposite end to the inner end of an internally threaded opening 31 formed in a hollow cover plate 32. Within the hollow cover plate 32 is provided a helical coil spring 33 which is arranged to exert force against the outer end 34 of shoulder 26. In this way the shoulder 26 will always snugly press against the collar 27 irrespective of the relative expansion of the different burner parts over the wide temperature range encountered during operation of the furnace 12. The cover plate 32 is sufficiently large to close the enlarged opening or well 28 and is secured at 35 to the outer metallic shell 36 of the furnace 12. A suitable combustible mixture is delivered from a source of supply such as a mixing machine through conduit 37 connected to the internally threaded opening 31 of the burner. The conduit 37 for supplying combustible gas mixture to the burner may be arranged in any desirable manner, and suitable controls may be provided to adjust the pressure and the rate at which the combustible gas mixture is supplied to the burner. The combustible gas mixture passes through the short length of flexible tubing 30 and metal tube 29 into the burner tube 25.

At the inner end of tube 25 is secured a distributor 38 for sub-dividing the combustible gas mixture into a plurality of gas streams which are discharged from ports at the surface of the distributor where they are ignited. The burner flames project outwardly from the distributor 38 about the entire peripheral surface thereof. The combustion space 24 is of such shape and the flames project outwardly at such an angle from the axis of the burner that the flames are closely adjacent to and follow the cup-shaped refractory wall to heat the latter to incandescence.

The distributors 38 are made of high temperature refractory material and are preferably assembled from a plurality of parts as best shown in Figures 2 to 4 of the drawing. Referring to those figures it will be seen that there is provided a hollow cylindrical body member 39 having an enlarged portion 41 at one end thereof. This member is provided with threads 42 on its surface by means of which it can be threaded into the tube 25 through which the combustible mixture is supplied. The surface of the body 39 has formed in its periphery a plurality of grooves 43 which extend axially of the member and turn radially outward as shown at 44 where they terminate at the surface of the enlarged portion 41. It will be seen from an inspection of the drawing that when the distributor is threaded into tube 25 the ends 44 of these grooves will form ports that are directed radially into the

cup 24. Extending through the center of the body 39 is a plug 45 that is smaller in diameter than the opening in the body, but which is centered with respect thereto by means of a plurality of radially extending fins 46, shown herein as being four in number. These fins extend axially of the plug to provide a plurality of passages through the interior of the member 39 as shown at 47 in Figure 4 of the drawing. The plug is located axially with respect to the body member 39 by enlarged portions on the ends of the fins that engage against a beveled surface at the end of the body, as shown at 48. The other end of the plug projects beyond the member 39 and is threaded as shown at 49 to receive a cap 49. This cap is threaded on the plug to hold the three parts of the distributor tightly in assembled relation. The face of the cap which engages the right end of the member 39, as shown in Figure 2, is provided with an extension the same diameter as the enlarged portion 41, which extension has formed in it a plurality of radial grooves 51. These grooves also form passages through which the combustible mixture can be directed in a radial direction into the cup. The parts may be assembled so that ports 44 and 51 are in axial alignment or are displaced circumferentially with respect to each other.

In the operation of the burner disclosed herein the combustible mixture is supplied under a suitable pressure, that will vary with various installations, through the tube 25. The mixture then passes through the passages formed by grooves 43 as well as through the radial passages 51 into the cup 24 of the burner. The mixture discharged from passages 44 is ignited and sweeps along the entire surface of the cup as it is burning. The mixture from passages 51 starts to burn as it leaves the distributor and is carried along with the flames from the first-mentioned passages to increase the heat release from the burner. The uniform incandescence produced in the cup by the burning fuel is not apparently affected whether the two rows of ports are in axial alignment or staggered. Radiant heat of high intensity is projected into the furnace chamber and on the work contained therein from the incandescent cup. Heat is also produced by the hot products of combustion which pass from the burner into the space to be heated.

By providing a double row of fuel ports the total port area of the burner is increased without changing the area of individual ports. This means that the capacity of the burner for a given pressure of fuel supply is increased appreciably, but the fuel pressure at which backfire will occur is not increased.

When a burner of the type disclosed herein is used with a gas having a slow ignition characteristic, such as natural gas, there is a tendency for ignition to start at some distance from the mouth of the ports so that there is a cold ring in the cup closely adjacent to the distributor. This is overcome by having the cap 49 made of a diameter larger than the diameter of the portion 41 of body member 39. It is believed that the overlapping portion of the cap creates a turbulence in the mixture to speed up ignition at the exit of the passages so that the under surface of the overhanging part of the cap will be heated to incandescence and thereby serve to pilot the flames. In any event, with this construction the gas mixture is ignited immediately upon leaving the ports. In this fashion a slow burning gas is ignited as soon as it leaves

the ports, thus heating up the entire cup and doing away with the above-mentioned cool ring around the distributor.

When a distributor of the type described above is used the diameter of the cap 49 is larger than the diameter of the tube 25 so that the distributor has to be removed from the tube before the latter can be withdrawn from the burner. When using the burner with a gas having fast ignition characteristics, such as city gas, it is not necessary to have the cap of the distributor larger in diameter than that of the tube 25 so that the entire assembly can be withdrawn from the wall of the furnace. Such a construction is shown in the distributor of Figure 5. This distributor also differs from that described above in that provision is made for increasing the number of rows of ports through which the mixture may be discharged.

Spaced between the cap 49a and the body member 39 is an annular member 52 which abuts the outer or right end of body 39 in Figure 5 of the drawing. This member is provided with a plurality of radially directed grooves 53 that form passages through which the mixture can be discharged into the cup. Cap 49a is provided with radially directed grooves 54 similar to the grooves 51 described above. Therefore, the distributor of this embodiment is provided with three axially displaced rows of ports through which the combustible mixture can be discharged into the cup of the burner. The mating faces of the disc 52 and the head 49a are formed as shown at 55 so that the disc cannot be displaced radially with respect to the cap. Thus, all of the parts are held in axial alignment during the operation of the burner. It should be noted that whether the distributor is provided with two rows of ports as in Figure 2 or with three (or more) rows as in Figure 5 would depend upon the desired capacity of the burner, rather than upon the diameter of the cap or upon the type of fuel used.

In the burner described above, provision is made to supply a combustible mixture through tube 25 from any suitable source. With a construction of this type the fuel is generally supplied to a group of burners from a mixing machine which will proportion the air and gas correctly to produce a complete mixture. In some cases it is desirable to have the mixture supplied individually to each burner from an inspirator. A construction of this type is shown in Figure 6 of the drawing. This figure also shows a slightly different arrangement of parts for forming the cup itself.

Referring to Figure 6 it will be seen that there is provided the burner block 21 as above described. The inner cup member shown therein as 56 is in this case, provided with a frustroconical extension 57. Received by this extension in concentric relation therewith is a similarly shaped insert 58. To the left of the insert is a base block 59. With an arrangement of this type one or more inserts of various thicknesses can be used depending upon the thickness of the furnace walls. The block 56 forming the inner portion of the cup is of refractory material, whereas the base block 59 can very well be of insulating material. The insert 58 can be either insulating or refractory depending upon the temperatures of the furnace and the thickness of the furnace wall.

Surrounding the base 59 is a casting 61 that is fastened as by bolts 62 to the shielding 36

forming the outer portion of the furnace wall. This casting is provided with an axial opening through which the Venturi-tube 63 of an inspirator is inserted. The tube is provided with an integrally formed flange 64 that is bolted to the casting 61 as at 65. It is noted that gaskets can be used between the casting and the furnace wall as well as between the flange 64 and the casting in order to insure a pressure-tight connection between these parts. The right end of the inspirator tube 63 has threaded thereon a distributor holder 66 formed of metal alloy that can withstand the high temperatures produced at the base of the cup. The distributor 38, which can take the form of the distributor disclosed in Figure 2 or the distributor disclosed in Figure 5, is threaded into the holder 66 as shown in the drawing.

The left end of the inspirator tube is provided with a web 46 that holds a sleeve 68 through which gas is supplied under suitable pressure from a pipe 71. The right end of the sleeve 68 is provided with an orifice member 69 having in it an orifice of the proper diameter for the type of gas that is being used and for the pressure under which the gas is supplied. Air for combustion is drawn through the left end of the sleeve 63 by the velocity head of gas leaving the orifice member 69. The ratio of gas and air forming the combustible mixture can be varied by changing the position of an air shutter 72 with respect to the open end of the inspirator tube 63.

The operation of inspirators is well-known. Gas under a suitable pressure is supplied through pipe 69 and entrains air as it leaves the orifice so that the complete mixture is supplied to the distributor. Some of the pressure head of the gas is lost due to the work expended in entraining the air so that it is impossible to have the same pressure immediately behind the distributor that is obtained in the supply. Because of the low pressures that are obtainable with inspirators it has been extremely difficult to force enough of the mixture through the distributor into the cup to obtain the desired heating effects. With a distributor of the type disclosed herein, however, the port area is increased over what has previously been possible to obtain so that the capacity of the burner is greatly increased.

A burner of the above-described type having a cup diameter of 12 inches and provided with a distributor 3 inches in diameter was tested. The distributor had two axially displaced rows of ports with 24 ports in each row and a total port area of 1.41 square inches. In operating the burner on city gas having 565 B. t. u. per cubic foot, gas was supplied through an inspirator at 9.5 pounds per square foot. The inspirator was so adjusted that an air-gas ratio of 5 to 1 was obtained and the pressure back of the distributor was 2 $\frac{1}{2}$ inches water column. With such operation 621 cubic feet of gas were burned per hour in a closed combustion space to release 351,000 B. t. u. A cup temperature of 2550° F. was obtained, and at a cup temperature of 2200° F. backfire occurred at $\frac{3}{8}$ inch of water column pressure back of the distributor.

From the above description it will be seen that the novel distributor member described herein may be used with radiant type burners to increase the capacity thereof. The parts of the distributor may easily be formed of suitable high temperature material such as a mullite composition by standard ceramic methods. The parts of the

distributor may be assembled before firing or may be assembled after firing and then cemented together. In either case the result is a substantially one-piece construction. Distributors of the type described are preferably used in burners of relatively large size and are usually three inches or more in diameter.

While in accordance with the provisions of the statutes, I have illustrated and described the best form of embodiment of my invention now known to me it will be apparent to those skilled in the art that changes may be made in the form of the apparatus disclosed without departing from the spirit and scope of the invention, as set forth in the appended claims, and that in some cases certain features of my invention may be used to advantage without a corresponding use of other features.

What is claimed is:

1. A burner comprising in combination a block of refractory material having a cup-shaped depression in one face thereof and an opening extending from the base of the cup to an opposite face thereof, a cylindrically shaped distributor member formed with a plurality of grooves on its surface extending axially from one end thereof and terminating near the other end thereof, said member being formed with an axial passage extending from said one end to a point nearer said other end than said grooves terminate, said member having a plurality of passages extending radially from the surface thereof to the end of said axial passage, and means to hold said member in the opening of said block with the ends of said grooves in said cup.

2. A distributor for a burner comprising a cylindrical body having a first portion of a first diameter extending from one end toward the other, and a second portion of a larger diameter joining said first portion, the surface of said first portion being formed with a plurality of axially extending grooves which bend in a radial direction to terminate at the surface of said second portion, said member being formed with an axial bore extending from said one end, and a plurality of radial passages extending from the surface of said second portion to said axial bore.

3. The combination of claim 2 in which said body has a third portion of larger diameter than said second portion and joining the same, said third portion extending radially outward beyond the point at which said passages terminate.

4. A distributor for a burner comprising a tubular part having an enlarged portion on one end thereof, a plurality of axially extending grooves formed on the exterior surface of said part, each groove extending from one end of said part and terminating in a substantially radial direction at the surface of said enlarged portion, a cylindrical member having axial flanges thereon received in the bore of said part and having a portion extending beyond the same, said flanges engaging one end of the part to locate the cylindrical member and part relative to each other, and a cap having a flat face attached to the extending portion of said cylindrical member and engaging with its face the end of said enlarged portion of said part to close the same, said cap being formed with radial grooves on its face, the radial grooves extending from the edge of the cap to the central opening of said part.

5. The combination of claim 4 in which said cap is larger in diameter than said enlarged portion of said part whereby the cap extends beyond the outer ends of said radial grooves.

6. The combination of claim 4 in which there is provided an annular member between said part and said cap, said annular member being formed on the face thereof engaging said part with a series of radially directed grooves forming passages from the central bore of said part to the surface of said annular member.

7. In a burner, the combination of a block of refractory material having a cup-shaped depression formed in one face thereof and an opening extending from the base of the depression to an opposite face thereof, a tubular member received in said opening and through which fuel is supplied, fuel distributing means mounted on the end of said member and including a ceramic disc having opposite flat faces and an opening in the center thereof and a plurality of radially extending grooves formed on one face thereof extending from said opening to the periphery of the disc, cylindrical means having an axial opening and a flat face extending substantially perpendicular to said opening and of the same diameter as said disc, the grooved face of said disc engaging the flat face of said cylindrical means to form a plurality of radially extending passages, a ceramic cap having the same diameter as said disc engaging the opposite face of said disc, means to fasten said cylindrical means, said disc and said cap together as a unit, and means on said cylindrical means to mount said unit in the end of said tubular member and coaxial thereto so that the outer ends of said passages are in said depression adjacent to the base thereof, whereby fuel can issue from said passages into said depression in a plurality of radially extending jets to be burned therein.

8. A fuel distributor for a burner comprising a tubular member through which a fuel and air mixture is supplied, means attached to said member to discharge the mixture in a plurality of substantially radially directed jets including a part in threaded engagement with said tubular member, said part having an axial opening and a flat face perpendicular to said opening, an annular ceramic disc having flat faces the same diameter as the face of said part, said ceramic disc being formed on one face thereof with a plurality of radial grooves extending from the center to the periphery thereof, said grooves being at least as wide at the periphery of the disc as they are at the center thereof, a cup shaped ceramic cap member having a flat face the same diameter as the face of said part to close the opening in said disc, said face being provided with grooves extending radially from the periphery to the center thereof and means holding said disc with the grooved face thereof against the flat face of said part and the grooved face of said cap member against the opposite face of said disc, said holding means extending centrally of the assembly between said part and said cap.
